PAPER SHREDDER

William Macowski, Caldwell, N.J., assignor to Ketcham
& McDougall, Inc., Roseland, N.J.

Filed May 14, 1971, Ser. No. 143,743

Term of patent 14 years

Int. Cl. D18—99

U.S. Cl. D55—1

FIG. 1

FIG. 4

FIG. 2

FIG. 3

FIG. 6

FIG. 5

FIG. 1 is a perspective view of a paper shredder embodying my new design;

FIG. 2 is a plan view of the paper shredder illustrated in FIG. 1;

FIG. 3 is a front view of the shredder illustrated in FIG. 1;

FIG. 4 is a right side elevational view of the shredder illustrated in FIG. 1;

FIG. 5 is a left side elevational view of the shredder illustrated in FIG. 1; and

FIG. 6 is a bottom view of the shredder illustrated in FIG. 1.

I claim:

The ornamental design for a paper shredder, as shown.
